UNITED STATES PATENT OFFICE.

MARTIN FRANK, OF BROOKLYN, NEW YORK.

COMBINATION HANDY TOOL.

Application filed July 17, 1924. Serial No. 726,461.

To all whom it may concern:

Be it known that I, MARTIN FRANK, a citizen of Hungary, residing at Brooklyn, in the county of Kings and State of New York, have invented certain new and useful Improvements in a Combination Handy Tool, of which the following is a specification.

This invention relates to a combination handy tool adapted for general use in homes, offices, stores, factories, garages, shops, or in any place desired.

The invention has for an object the provision of a novel tool of this sort, of simple construction and having the various operating or cutting elements thereof arranged in a novel manner.

For further comprehension of the invention, and of the objects and advantages thereof, reference will be had to the following description and accompanying drawing, and to the appended claims in which the various novel features of the invention are more particularly set forth.

Fig. 1 of the drawing is a face view of my improved tool;

Fig. 2 is an edge view thereof;

Fig. 3 is a transverse sectional view taken on the line 3—3 of Fig. 2;

Fig. 4 is a like view to Fig. 3, but showing the device as in use in opening cans;

Fig. 5 is a face view of the blank from which the main element of my improved tool is formed; and

Fig. 6 is a fragmentary edge view showing a safety-razor blade mounted on the tool.

In constructing my improved tool I make use of a main sheet-metal element which is cut to the form of an elongated strip 10 as shown in Fig. 5. A slot 11 is entered for a distance into this element from one end thereof and midway between the sides thereof, while the other end is cut to form a pointed member 14 near one edge and a curved blade 15 near the other edge, this blade having its convex edge suitably sharpened to form a can-opener. This member 10 is folded along its median line to assume the doubled form shown in Figs. 1 and 2, and the two halves or leaves of the member may be secured together at suitable points by the rivets 16. The blade 15 is turned out at right angles to the main member, which forms the shank of the tool. At the slotted end of the shank the two parts thereof are spread apart as

shown at 10' in Fig. 2 to straddle a handle element. This handle element is in the form of a flat bar 18 which is formed with a suitable aperture midway between its ends 60 through which may be passed a bolt 19 which extends also through suitable apertures 20 in the parts 10', and thereby secures the handle member on the shank.

This handle member may be constructed to 65 perform various functions, having a scale 22 formed along one edge, which edge is notched as at 23 to enable a metal crown cork on a bottle to be gripped and the crown cork forced off the bottle. It is also formed 70 at one end with a notch 24 which is suitably shaped to sharpen knife blades which may be drawn therealong, while this end of the handle may be magnetized to facilitate picking up small metal objects. A triangular 75 aperture 25 is also formed in the handle to enable the heads of nails to be gripped and the nails pulled.

When utilizing the point 14 to pierce objects it may be desirable to hammer on the 80 tool and I therefore provide a removable cap which may be slipped over the top edge of the handle to receive the blows of the hammer. This removable element is in the form of a bar 28 of generally channeled 85 cross-section and having its flanges turned inward to engage slidably in grooves 29 in the sides of the handle 18. To yieldingly retain the cap against displacement from the handle I may fix to the inner faces of the 90 shank elements 10' the flat spring fingers 30 which extend longitudinally therefrom and which are adapted to spring into recesses 31 in the underside of the bar to retain the latter in position on the handle. I may utilize 95 these spring fingers to mount a safety-razor blade in the shank, in place of the handle 18, for use in cutting corns or various other purposes. To this end the spring fingers are formed with suitable apertures and are 100 adapted to receive the razor blade 33 therebetween. A bolt 19', may be passed through the apertures in the fingers and in the razor blade to secure the latter in place.

In utilizing my improved tool as a can-opener the pointed member 14 is first forced into the can top 34 and is then withdrawn and the blade 15 is inserted therein as indicated in Fig. 4, and the shank is given an oscillatory and transversely advancing 110 movement to cause it to cut the top. The manner of use of the various other parts of

my improved tool will be apparent from the foregoing description.

Having thus described my invention, what I claim as new and desire to protect by Letters Patent of the United States is as follows:—

1. A device of the class described comprising a shank having a pointed end, and a curved cutting blade extending at right angles from said shank adjacent said end, said shank and blade being formed of a single piece of sheet metal folded longitudinally along its median line to form two leaves, said point being formed on one of said leaves and said blade on the other leaf.

2. A device of the class described comprising a shank having a pointed end, and a curved cutting blade extending at right angles from said shank adjacent said end, said shank and blade being formed of a single piece of sheet metal folded longitudinally along its median line to form two leaves, said point being formed on one of said leaves and said blade on the other leaf, said leaves being spread apart from one another on the slotted end of the shank to receive a handle therebetween.

In testimony whereof I have affixed my signature.

MARTIN FRANK.
